UNITED STATES PATENT OFFICE.

WILLIAM W. FAY, OF JEFFERSON CITY, MISSOURI, ASSIGNOR TO HIMSELF
AND CHARLES O. ADAMS, OF SAME PLACE.

RAIL-JOINT.

SPECIFICATION forming part of Letters Patent No. 223,899, dated January 27, 1880.

Application filed November 28, 1879.

To all whom it may concern:

Be it known that I, WILLIAM W. FAY, of Jefferson City, in the county of Cole and State of Missouri, have invented a new and Improved Railway-Rail Joint, of which the following is a specification.

The object of my invention is to form a strong and substantial joint between the ends of adjoining railway-rails.

10 The invention consists in connecting the ends of adjoining rails together by means of a metal plate inserted in slots in the adjacent ends, and also in fastening and tightening said connecting-plate in its place by means of laterally-driven dovetailed wedges.

15 In the accompanying drawings, Figure 1 is a vertical longitudinal section, taken on line $x-x$ of Fig. 2, of my improved railway-rail joint; and Fig. 2 is a vertical cross-section of 20 the same on line $x'-x'$ of Fig. 1.

Similar letters of reference indicate corresponding parts.

25 Referring to the drawings, A A' are the ends of two railway-rails. In these ends A A' are central longitudinal vertical slots, $a a'$, extending through the base b of the rails and upward into the webs c to the base of the heads d .

30 The ends A A', respectively, are likewise provided with transverse dovetailed slots $e e'$, made through the webs c , with the lower dovetailed sides, f , of said slots next to the bases b of the rails.

B is a steel plate inserted in the vertical slots $a a'$, so as to join the ends A A' of the 35 rails together. C C' are dovetailed wedges, which are driven, respectively, through transverse slots $e e'$ under the lower edge of steel plate B. C' represents the ties on which the rails rest.

40 The ends A A' are held together by the plate B, which is driven firmly up against the top of slots $a a'$ by wedges C C'. The said plate B also prevents the ends A A' from becoming displaced or detached vertically or laterally, and, further, it supports the ends A A' against sagging.

45 When the wedges C C' are driven through slots $e e'$ they are prevented from coming out by a rod, g , passed through holes h in the 50 smaller ends of said wedges, said rod having its end i bent to prevent it from slipping out of the said holes h .

55 Having thus described my invention, I claim as new and desire to secure by Letters Patent—

As an improvement in railway-rail joints, the rail ends A A', provided, respectively, with slots $a a'$ and $e e'$, in combination with the steel connecting-plate B and wedges C C', substantially as described.

WILLIAM W. FAY.
